HAIR BRUSH

Murray Schotland, New York, N.Y.

Application February 17, 1959, Serial No. 54,646

Term of patent 3½ years

(Cl. D86—10)

Fig. 1 is a rear view of a hair brush, showing my new design;

Fig. 2 is a front view thereof; and

Fig. 3 is a side view thereof.

I claim:

The ornamental design for a hair brush, substantially as shown.
